CLAIM

The ornamental design for a journal, as shown and described.

DESCRIPTION

FIG. 1 is a perspective view of a journal, showing the new design in a closed configuration;

FIG. 2 is a perspective view thereof, illustrated in an open configuration;

FIG. 3 is a front elevational view of FIG. 1;

FIG. 4 is a top plan view of FIG. 1;

FIG. 5 is a bottom plan view of FIG. 1;

FIG. 6 is a rear elevational view of FIG. 1;

FIG. 7 is a left-side elevational view of FIG. 1; and,

FIG. 8 is a right-side elevational view of FIG. 1.

The broken lines showing a lock and pen in FIG. 1 depict environmental matter while the design is in use, and form no part of the claimed design.
